TREATMENT OF HYDROCARBON OILS

Bernard J. Flock and Edwin F. Nelson, Chicago,
Ill., assignors to Universal Oil Products Com-
pany, Chicago, Ill., a corporation of Delaware

Application August 14, 1936, Serial No. 95,996

1 Claim. (Cl. 196—10)

This invention relates particularly to the treatment of hydrocarbon gases produced incidental to the cracking of the heavier portions of petroleum oils for the primary object of producing gasoline, although the process is applicable also to treatment of certain gaseous hydrocarbon fractions to be later more fully described which are produced when cracking other heavy hydrocarbonaceous materials such as those produced in the primary distillation of coal, lignites, shale, etcetera.

More specifically, the invention is concerned with a modification and an improvement in catalytic processes which are aimed at the conversion of the lower boiling and normally gaseous olefins present in cracked products into liquids of gasoline boiling range. Owing to the generally dehydrogenating character of cracking reactions, there are considerable percentages of olefins present in all of the products of cracking from the gases down through the lighter liquids to the heavier residua. The character of the unsaturation in the total products and in the various fractions will depend upon the character of the original charging stock to the cracking process and the conditions of severity employed in respect to temperature, pressure and time of exposure to cracking conditions. This unsaturation embraces not only compounds of an open chain structure but also compounds characterized by closed rings of an aromatic or hydroaromatic character.

The unsaturated character of cracked products is generally advantageous from a standpoint of the quality at present most desirable in automotive fuels, since the anti-knock value which is commonly expressed as octane number increases generally as unsaturation increases though there are various digressions from this general rule in the case of isomeric or condensed structure hydrocarbons. The present process is concerned with the efficient utilization of the lower boiling olefinic products of cracking whereby they are polymerized by the use of selected catalytic contact materials and a particular mode of operation to produce optimum yields of the polymer products which are of the highest possible anti-knock value. Owing to the requirement of a limited vapor pressure in saleable gasolines, there is generally an overproduction of hydrocarbons of 3 and 4 carbon atoms, and by the present process the olefinic constituents of these so-called propane-butane mixtures are utilized as a source of additional yields of high anti-knock material which can be blended with the total gasoline

products from the cracking process or with other motor fuels of inferior anti-knock value.

In one specific embodiment, the present invention comprises the polymerization of the olefins in the overhead fractions from stabilizers operating upon primary cracked distillates for the removal of the unnecessary excess of 3 and 4 carbon atom fractions by separately and selectively contacting the gaseous and the liquid phases from the overhead distillate receiver of the stabilizer with solid phosphoric acid catalysts.

From the foregoing brief statement of the character and scope of the present process it will be obvious to those familiar with such matters that the details of operation will be capable of considerable modifications without departing from the spirit of the invention. However, for purposes of illustration and for more accurately defining the process, the attached diagrammatic drawing has been provided which indicates in general side elevation by the use of conventional figures an arrangement of apparatus in which the process may be conducted, though it is not intended to limit the scope of the invention in exact correspondence therewith.

Referring to the drawing, line 1, containing control valve 2, is for the admission of primary cracked naphthas which are to be stabilized to a given vapor pressure while utilizing the overhead light fractions as a source of olefin containing materials to be polymerized. As a rule, since substantially all cracked naphthas are condensed and collected under plant pressure, which may be anywhere from 100 to 500 pounds per square inch, there will be relatively small percentages of light gases such as hydrogen, methane, ethane, and ethylene in the primary distillates which are reheated for the stabilizing step, so that these lighter gases which are not affected by polymerizing catalysts will commonly be present in only negligible quantities and the overhead subjected to polymerization will therefore be in a sense a concentrate of 3 and 4 carbon olefins and possibly some heavier which are readily polymerized by the preferred catalysts.

As a rule primary cracked distillates are stabilized at pressures of approximately 100-150 pounds per square inch and heated to approximately 225-275° F. before they are admitted to the stabilizing column. The top temperature may be held at approximately 100-150° F. (depending upon the percentage of low boiling fractions present) by cooling devices or the return of overhead reflux and the bottom of the tower may be held at 275-325° F. by means of indirect con-

tact heaters or other reboiling devices to permit accurate stripping of the gasolines or naphthas. The draw line 4, containing control valve 5, permits the withdrawal of stabilized products from stabilizer 3.

The overhead fractions pass in vapor form through line 6, containing control valve 7, and are condensed during passage through a condenser 8 after which liquid and vapor fractions pass 10 through line 9, containing control valve 10, to a receiver 11. In this receiver there will be a partition of liquid and vapor phases which will be due to the fact that the overhead fractions are of a considerable boiling range and generally still contain 15 some compounds which are normally gaseous under the conditions obtaining in the receiver.

The principal feature of the present invention appears at this point and consists in the separate treatment of the vaporous and liquid 20 phases present in the stabilizer receiver. There are numerous advantages in this procedure, one of which is that the composition of the two 25 phases varies in respect to higher olefin content and another of which is that there is an advantage in pumping liquid material particularly when the use of high pressures are desirable in subsequent polymerization, since liquid pumps are more efficient and more easily controlled than vapor phase compressors. The separate treatment 30 of the liquid and vapor phases therefore permits of greater flexibility and better control of the polymerization process to produce optimum yields of liquid polymers from overhead distillates from stabilizers which are commonly known as stabilizer refluxes.

Following the process as outlined in the drawing, the vapor phase from the stabilizer is picked up by a compressor 23 from line 21, containing control valve 22, and pumped through a line 24, 40 containing control valve 25, through a heating element 26 arranged to receive heat from a furnace 27 in which the vapor fractions are brought to a suitable temperature for their polymerization. With the preferred catalyst to be presently 45 described and for the average composition of mixtures produced at this point temperatures from approximately 250-450° F. are generally most suitable and by proper manipulation of such controllable factors as pressure, time of 50 contact and efficiency of catalyst, the mixtures may be either selectively polymerized to remove the olefins in order of their reactivity or may be subjected to average conditions to produce separate fractions varying in physical and chemical 55 conditions.

According to the present process the liquid condensate in receiver 11 passes through a line 12, containing control valve 13, to a pump 14, which serves the double purpose of returning a portion of the liquid to the top of the stabilizer by way of line 15, containing control valve 16, and line 17, containing control valve 18, and the remaining portion which may be designated as the "make" of the plant to a second catalytic 60 polymerizing unit by way of line 19, containing control valve 20, and into a primary heater 49 disposed to receive heat from a furnace setting 65 50.

The catalysts which are preferably employed 70 to effect the polymerization of olefins in the two phases according to the present process are of a very special character and their use is considered a special feature thereof. These catalysts are designated generally as "solid phosphoric acid" catalysts and are made by the gen-

eral steps of mixing an acid of phosphorus (usually the ortho or the pyro acid) with a substantially non-catalytic and usually siliceous adsorbent material until a rather stiff paste is obtained and then either calcining the pasty material under controlled conditions to produce a solid cake which is ground and sized to produce catalyst particles or which is first formed into small particles by extrusion or pelleting methods and then calcined until particles of optimum characteristics in respect to quantity and character of phosphoric acid and its condition of fixation in the particles is assured.

In the primary mixing of phosphoric acids and adsorbents, ordinary temperatures may be 15 employed in case the ortho acid is used but in case the pyro acid is employed, somewhat elevated temperatures above its melting point are more suitable to insure its fluidity. Since the precalcining step in the preparation of the catalyst evidently tends to form an acid slightly over pyrophosphoric acid in respect to the degree of dehydration of the phosphoric anhydride, advantages in time are usually gained by starting with the pyro acid. In some instances, however, when it is desired to operate to more or less selectively polymerize and remove isobutene from cracked gas mixtures, weaker catalysts in which the ortho acid predominates may be better employed and it is comprised within the scope of the invention to employ this type of precalcined catalyst. The proportions of acid and adsorbent may also be varied so that precalcined mixes in which the acid constitutes a minor percentage by weight may be employed or in which it constitutes a major portion of the total weight of the composite. In the case of isobutene polymerization catalysts comprising 30% by weight of substantially only the ortho acid may be employed while in the case of polymerization of 40 propylene composites consisting of 70% by weight of an acid approaching the pyro acid in composition and 30% of adsorbent may be used.

Some of the preferred adsorbent materials which may be used with the phosphoric acids 45 are such materials as kieselguhr, bentonite clays, silica gel, and incidental materials such as the oxides of the alkaline earth metals and certain heavy metal halides such as zinc chloride which may contribute to the total effectiveness of the catalyst composites ultimately produced. Calcining may be conducted at temperatures as high as 600° F. and if necessary or desirable the calcined mixes may be subsequently contacted with superheated steam at temperatures of the order 50 of 450-550° F. to control the concentration of the adsorbed acid catalyst.

In the operation upon the vapor phase from the receiver heated materials pass through line 28, containing control valve 29 and through a 60 series of catalytic treaters typified by 30 and 33 in which the preferred catalysts are present as 65 filler and in which the olefines in the entering mixtures are converted into liquids by polymerization. Suitable operating conditions are temperatures from 350 to 550° F. and pressures of 100 to 300 pounds per square inch. The two 70 treaters shown are to indicate that any suitable arrangements may be employed either in series or parallel connection and there may be if desired intermediate separation of polymers and collection of individual fractions, or the total materials may be gradually polymerized during passage through a succession of treaters and finally subjected to fractionation. Line 31, con- 75

taining control valve 32, leads the total products from primary chamber 30 to a final chamber 33 and line 34, containing control valve 35 leads the final products to a fractionator 36 which may function to effect any separation of the products which may seem desirable. For example, nothing but stabilized gasoline boiling range liquid polymers may be withdrawn from the bottom of this fractionator through line 37, containing control valve 38, or a heavy portion of these polymers may be so withdrawn while the lighter portions are taken overhead as vapors or removed as a side cut.

The overhead from fractionator 36 passes through line 39, containing control valve 40, and a portion thereof is condensed during passage through a condenser 41, the condensed liquid along with uncondensed gases and vapors following line 42, containing control valve 43, to receiver 44 which has a fixed gas release line 45, containing control valve 46, and a liquid draw line 47, containing control valve 48, which may comprise in some instances propane-butane fractions containing a sufficient quantity of olefins to make further contacting with the catalysts desirable or which may be essentially paraffinic so that they are only utilizable if subjected to dehydrogenation to produce higher percentages of olefins.

The liquid phase from receiver 44 which has been pumped under considerable superatmospheric pressure through line 49 and valve 20 and preheated during passage through element 49 in furnace 50 will pass through a line 51, containing control valve 52, to a separate polymerizing plant which may, as in the case of the plant operating upon the vapor phase from the receiver consist of any suitable arrangement of polymerizing chambers typified in the drawing by 55 and 55' which are connected by transfer line 53, containing control valve 54. Owing to the greater ease of developing high pressure in the pumping of the liquid phase, it is practical to employ conditions which favor the primary selective polymerization of isobutane to form the olefin dimer which is hydrogenatable to the iso-octane designated as 2,2,4-trimethyl pentane. This may be accomplished for example by introducing the liquid mixtures at temperatures from ordinary atmospheric up to 200° F. under pressure of the order of 500-600 pounds per square inch so that the primary catalyst beds are operating upon material which is still essentially in liquid phase. By further modifying the conditions of operation, selective mixed polymerization of iso and n-butenes may be effected which in some cases produces ultimately the highest yields of high octane number hydrogenated products which apparently contain high percentages of 2,2,3-trimethyl pentane. Suitable conditions for this modified operation are temperatures from 275 to 325° F., pressures of 500 to 600 pounds per square inch, and contact time of 250 to 350 seconds. A later example will indicate the commercial possibilities of this type of operation.

As indicated in the drawing, although intermediate separation of selected polymer fractions may also be practiced, the total products from the second polymerizing unit pass through line 56 containing control valve 57 and are fractionated by fractionator 58 from which liquid bottoms are withdrawn through line 59, containing control valve 60. Overhead vapors follow line 61, containing control valve 62, and may be

partially condensed by condenser 63 after which the condensed liquids and uncondensed gases pass through line 64, containing control valve 65, to a receiver 66 having a conventional gas release line 67, containing control valve 68, and a liquid draw line 69, containing control valve 70.

The foregoing general description of a characteristic operation of the process has indicated some of its alternative modes of operation which may be employed to effectively produce selected polymer fractions from the stabilizer overhead. As already indicated the description is general in respect to some of the details of operation in the polymerizing units and is given merely to show the general features of the process. The following example is introduced to indicate the results obtainable by the separate and specific treatment of the liquid and vapor phases in the stabilizer of a cracking process.

The overhead naphtha distillate produced in a cracking plant operating upon topped crudes from Mid-Continent and West Texas fields was treated. The average gravity of the topped crude mixture was 25° A. P. I. and the cracking plant was operated at a temperature of 960° F. and a pressure of 200 pounds per square inch at the exit of the heating element. In stabilizing the overhead naphtha distillate, there was made available an amount of overhead propane-butane fraction equal to 3% by weight of the original oil charged to the cracking plant. The stabilizer reflux receiver was operated at 200 pounds gage pressure and a temperature of 100° F. and the following table indicates the composition of the total overhead reflux and the vapor and liquid phases, respectively, which were available for polymerizing treatment:

Composition of stabilizer overhead

Component	Percent in total overhead	Percent in 20% vapor phase	Percent in 80% liquid phase
Methane.....	2.9	9.0	1.4
Ethylene.....	3.3	6.1	2.6
Ethane.....	13.2	23.4	10.7
Propylene.....	22.1	19.8	22.6
Propane.....	33.2	30.4	33.8
Isobutane.....	4.2	2.5	4.6
Isobutane.....	6.4	4.1	7.0
n-butane.....	8.4	3.0	9.7
n-butane.....	6.3	1.5	7.5
Higher olefins.....	34.7	25.3	36.9

The vapor phase material from the stabilizer distillate receiver was contacted with solid phosphoric acid catalyst in a series of treating towers at a maintained average temperature of 425° F. and a pressure averaging about 175 pounds to produce approximately 4 gallons of 85 octane number polymer per 1000 cubic feet of mixture treated. This treatment of the vapor phase material was conducted without the use of a compressor to step up the pressure from that of the stabilizer reflux receiver.

Liquid phase material was pumped up to a pressure of 550 pounds per square inch and treated to produce selective polymer fractions. In the first treating stage the material was contacted with a solid phosphoric acid catalyst at a temperature of approximately 300° F. and for a time of contact of approximately 250 seconds. This caused a maximum of mixed polymerization between the isobutene and the n-butenes and produced approximately 8 gallons per 1000 cubic feet of entering mixture (calculated as a gas) of liquid polymer which when substantially completely hydrogenated showed an octane num-

ber of 97. Further treatment of residual gases in a succeeding stage at a temperature of 450° F. produced a further yield of 4 gallons of high octane number material.

5 From the above general summary of data it will be seen that there was an increased yield of 1% of gasoline material based on the charging stock to the cracking plant and 2% of the gasoline boiling range material since the yield of 10 gasoline from the cracking stock was about 50%. The overall increase in octane number by blending the liquid polymers was from approximately 68 to 70 which brought the plant product in this particular instance up to premium grade.

15 We claim as our invention:

A process which comprises stabilizing cracked hydrocarbon distillate to remove normally gaseous hydrocarbons therefrom, subjecting the

evolved gases to partial liquefaction to form a liquid phase of relatively high olefin content and a gaseous phase of lower olefin content, said stabilization and partial liquefaction being effected under substantial superatmospheric pressure, 5 supplying the liquid phase material, without lowering the pressure thereon, to a polymerizing zone and therein subjecting the same to catalytic polymerization in the absence of the material of said gaseous phase and under sufficient superatmospheric pressure to maintain a substantial portion thereof in liquid condition, supplying the gaseous phase material to a second polymerizing zone maintained under lower pressure than the first-named zone and subjecting the same therein 10 to vapor phase polymerizing conditions.
